(No Model.)

G. D. EDMONDSON.

SPECTACLE LENS CASE.

No. 253,356.

Patented Feb. 7, 1882.

UNITED STATES PATENT OFFICE.

GEORGE D. EDMONDSON, OF DETROIT, MICHIGAN.

SPECTACLE-LENS CASE.

SPECIFICATION forming part of Letters Patent No. 253,356, dated February 7, 1882.

Application filed April 25, 1881. (No model.)

To all whom it may concern:

Be it known that I, GEORGE D. EDMONDSON, of Detroit, county of Wayne, State of Michigan, have invented a new and useful Improvement in Spectacle-Lens Cases; and I declare the following to be a full, clear, and exact description of the same, such as will enable others skilled in the art to which it pertains to make and use it, reference being had to the accompanying drawings, which form a part of this specification.

My invention consists in a lens-package formed of an envelope adapted to hold two lenses side by side, and having two transverse lines or creases, along which it may be folded to bring the lenses face to face, the space between said lines or creases being adapted to receive a printed or written description of the contents of the package, as hereinafter more particularly described.

In the drawings, Figure 1 is a back view of an ordinary envelope; Fig. 2, a front view of the same with a double crease across its middle and having a set of lenses within it. Fig. 25 3 is a view of the envelope folded together along both the central creases. Fig. 4 is a case containing the said separate packages. Figs. 5 and 6 represent the package formerly used. Fig. 7 shows the old form of case and the method 30 of ascertaining the contents of any package.

Heretofore it has been customary, as shown in Figs. 5, 6, and 7, to inclose a set of lenses in an ordinary envelope, then fold the latter transversely across the middle line, so that the fold 35 shall present a sharp edge; and it has been customary to print or write the description of the lens upon the flat surface of the envelope, as shown. When these lens packages were placed in a larger case for the convenience of 40 the dealer, the sharp edges of the envelopes presented upward, as shown in Fig. 7, and there being no place at this edge to mark the contents, the latter marks had to be written or printed down on the side, and were only rendered visible by the dealer pushing aside the successive envelopes until he exposed and discovered the one bearing the desired description.

It is the object of this invention to correct 50 this difficulty and render the description always visible whenever the case is open.

To this end A represents an ordinary en-

velope. This envelope is previously or at the time of use given two transverse folds, which increase it along the two lines a a. The lenses 55 are then inserted, the envelope closed, and the envelope is then folded down along these middle creases, a a. The resulting package presents at its folded part a narrow flat surface, a', upon which is printed or written the number, description, &c., of the contained lenses. When these separate packages are placed in a box, as shown in Fig. 4, their upper surfaces 60 form a level top, and the marks upon the successive packages are always visible without 65 handling the packages themselves, the same as though they had been written or printed upon the separate lines of a continuous strip of paper.

The advantages of this improvement will be 70 apparent at a glance, for where frequently many dozens, or even hundreds of these lens-packages are grouped together in a case and subjected to constant handling and frequent changes by sales, &c., it is difficult to find what is wanted 75 and becomes a source of great annoyance to the dealer, while by this improvement all the difficulty is at once overcome.

In making these packages the envelopes may, if desired, be prepared with the middle 80 transverse part already printed, so that when folded the print will occupy the proper place, and the envelope may, if desired, be simultaneously indented or creased, so as to mark the place for and facilitate the folding.

By the term "envelope" I would have it understood that I mean any ordinary envelope or similar pocket.

What I claim is—

A lens-package consisting of an envelope 90 adapted to hold two lenses side by side, said envelope provided with two transverse lines or creases, along which it may be folded to bring the lenses face to face, and adapted to receive a printed or written description of the contents 95 between the said lines, substantially as described.

In testimony whereof I sign this specification in the presence of two witnesses.

GEO. D. EDMONDSON.
